UNITED STATES PATENT OFFICE.

ALFRED V. RYDER, OF NEW YORK, N. Y.

IMPROVEMENT IN TRUNKS.

Specification forming part of Letters Patent No. **69,488**, dated October 1, 1867.

To all whom it may concern:

Be it known that I, ALFRED V. RYDER, of the city, county, and State of New York, have invented a new and useful Improvement on Trunks, of which the following is a full, clear, and exact description, reference being had to the accompanying drawings, forming part of this specification, and in which—

Figure 1 represents a front view of a trunk constructed according to my improvement in a closed condition; Fig. 2, a side or end elevation of the same closed; Figs. 3 and 4, similar views of the trunk when open, and Figs. 5 and 6 vertical transverse sections of the same in its open and closed conditions.

Similar letters of reference indicate corresponding parts.

My improvement has reference to trunks constructed substantially similar, as regards their general character, to one described in Letters Patent of the United States issued to me on the 18th day of September, 1866, and in which the body of the trunk has its front upper or upper front portion made sectional by vertical and horizontal cuts dividing it from the remainder of the body, and said front upper or upper front portion hinged in its rear at top, so that it may be turned over upon the back upper portion of the trunk in opening the latter.

The nature of my invention, in this connection, consists, in combination with a hinged front upper or upper front portion, as referred to, of a back upper portion of the body having its front or drawers fitting therein constructed to bevel or recede in a downwardly direction, whereby while a wide mouth, facilitating access, is given to the base portion of the body the hinged or opening and closing front upper or upper front portion may be light and strong, yet roomy, and the trunk-handles be attached direct to the sides or ends of the trunk at a convenient altitude and position without interference by or with the hinged front upper or upper front portion.

Said invention also consists in an advanced position relatively to a center line of said hinged front upper or upper front portion, whereby not only is room established for a direct attachment of the handles, but when such

portion or lid is inverted in the opening of the trunk a shelf for outside stowage is formed in the rear of it.

Referring to the accompanying drawings, A represents the front upper or upper front portion of the trunk, hinged, as at *a*, to the rear upper portion, B, from which and the lower portion, C, it is divided by a vertical cut or cuts, *b*, and horizontal cut or cuts *c*, the vertical or downward cuts *b* being nearer the front than the back of the body or trunk and longer than the horizontal or other equivalently-running cut or cuts *c*. This gives a light and strong character to the front upper portion, A, which facilitates the opening and closing of the trunk, besides giving better protection against outward thrust or pressure at its sides, and admits of the trunk-handles D being attached centrally direct to the sides or ends of the trunk at a proper and convenient altitude for carrying the trunk without interference by or with the opening and closing portion A; also, when the lid or portion A is inverted in the opening of the trunk, forms a shelf, S, in rear of the lid on the top of the portion B, for stowing papers or other articles out of sight between the lid and the wall. But this construction, were it not for a special configuration or receding character given to the front of the rear portion, B, would choke or contract to an inconvenient extent the mouth *d* of the base or lower portion, C, that is shown fitted with a lid, E, and would give too little capacity to the front upper portion, A, whereas it is desirable that all three main compartments or portions A, B, and C should be roomy without objectionable size or shape to the trunk generally. I accordingly construct the front of the rear portion, B, which portion may be fitted with drawers F, of a receding character—say by beveling or sloping it downward toward the back of the trunk, so that it admits of a wider mouth, *d*, to the lower portion, C, than is due to the vertical cut *b*—that is, than were the faces of the drawers F of the rear upper portion, B, in line with the cut or cuts *b*—while such construction detracts but little from the capacity of the compartment or portion B, and establishes a nearer approximation to equality of capacity between the portions A and B with.

out entailing a wide exposure at its sides or ends of the front upper portion, A, thereby reducing its liability to being forcibly pressed inward and giving room for a direct central attachment of the handles D to the body of the trunk at a proper altitude to prevent swaying of the trunk when being lifted or carried, likewise rendering light and easy to open and close the hinged portion A, which, to open the trunk, is inverted or turned up over upon the rear portion, B, as represented in Figs. 3, 4, and 6. The portion A is also shown as carrying a hinged tray, G, fitted with a lid, e, and having projecting from its front an extension, f, of the tray, and it may be pocket-book g, the shelving or receding of the faces of the drawers F or front of the rear upper portion, B, admitting of such projection or projections, which adds materially to the capacity of the front upper portion, A, within a light, strong, and compact construction of the shell or outer frame-work of said portion.

To prevent leakage of rain through the joint formed by the cut or division of the front upper form, the back upper portion—rubber or otherlike packing—may be attached or inserted

beneath metal straps or bands arranged on the outside of the trunk and so as to overlap said joint.

What I here claim, and desire to secure by Letters Patent, is—

1. In a trunk the body of which is composed of three main portions or compartments, A, B, C, the front upper or upper front one, A, of which is hinged, as at a, and made to open and close, as described, constructing the front of the rear portion, B, of the shelving or receding character relatively to the dividing cut or cuts b, substantially as and for the purpose or purposes herein set forth.

2. Hinging the front upper or upper front portion, A, when the same is arranged to open, as described, relatively to the remaining portion or portions of the trunk, at a point or in a line which is in advance of a vertical center through the width of the trunk, essentially as specified.

ALFRED V. RYDER.
